GARMENT

Filed Jan. 13, 1926

FIG. 1.

FIG. 2.

FIG. 3.

FIG. 4.

INVENTOR.
Gertrude G. Chick
BY
Carlo P. Griffin
ATTORNEY.

UNITED STATES PATENT OFFICE.

GERTRUDE G. CHICK, OF SAN FRANCISCO, CALIFORNIA.

GARMENT.

Application filed January 13, 1926. Serial No. 80,858.

This invention relates to a garment, and its object is to provide means for the support of the garment, either a pair of overalls with a high bib, or merely an apron, which will 5 hold the garment flat against the body and the support will not slip off the shoulders.

Another object of the invention is to provide means whereby the supporting straps may be disconnected from the garment at 10 either end. Ordinarily the connection at the top of the bib is a buckle hook, while the connection at the lower end of the strap is made with snap fasteners.

I do not claim broadly the idea of supporting garments with shoulder straps, for the 15 reason that many forms of shoulder straps have been previously used, but none of which are very satisfactory because of the fact that they are usually made of narrow tapes, and 20 are not at all fitted to the body so that they act merely as a string would act, and do not adequately hold the garments flat, nor are they so shaped as to prevent the straps from slipping off the shoulders.

25 In the present instance, the straps are so cut as to cross each other at the back of the wearer, and are so shaped as to lie flat on the body, both in the front and on the back. They are cut with a sufficient spring of the 30 goods to cause the pull upon the straps, not only to cause the strap to lie flat, but to cause the garment to have the strap ends when attached to lie flat on the body, while the attachment to the garment is so arranged as to prevent the possibility of the 35 strap from slipping off when it has been once placed in position.

Another object of the invention is to provide a close fitting supporting garment of 40 the character mentioned, which will allow any desired movement of the body without displacing the shoulder straps, and without wrinkling them, whereby the garment is made uncomfortable to wear.

45 Another object of the invention is to provide a close fitting garment of the character mentioned which will be supported entirely from the front piece by the shoulder straps, and which is so arranged as not to bind the 50 body uncomfortably in any way and to permit any desired looseness of the garment so there will be no strain or pulling on the garment at the waist line of the wearer.

An embodiment of the invention is shown 55 in the accompanying drawings in which the

same reference numeral is applied to the same portion throughout the several figures of the drawings, and of which there may be modifications:

Figure 1 is a back view of the garment 60 and its supporting straps as applied to a wearer.

Figure 2 is a front view of the garment with its straps as applied to the wearer, and the garment may be of any desired kind, as 65 for example, a pair of overalls, an apron, or a slip-over dress, and,

Figure 3 is a plan view of the strap for the support of the garment, the direction of the warp of the goods being illustrated in 70 broken lines to show the spring with which the strap is cut.

Figure 4 illustrates the manner of cutting to cause the bib to lie flat, and showing the attachment of the strap thereto. 75

It will be apparent from a consideration of fitting garments to persons that it is impossible to fit an extended strap around the curved body portion of a person if that strap is made of a piece of material which is cut 80 parallel to the length of the warp and weft of the goods since on the user the plane surface of such a strap will be tight along one side and loose along the other side with the result that if anything more than a narrow 85 tape is made use of, the entire strap will bunch up like a string instead of lying flat. This condition makes it necessary to cut the supporting strap from the goods in such a way as to give the goods the necessary spring 90 due to cutting on the bias to allow the surface of the strap to lie flat upon the curved body surfaces in order to aid in holding the strap flat. It is also necessary to make one end considerably wider than the other, 95 which widening not only aids in holding the garment flat, but also enables its attachment to the garment to be so made as to aid in holding the strap itself.

The numeral 1 indicates the lower portion of the garment the bib of the garment being indicated at 2. On each side of the bib there are four snap fasteners at the waist line, 4, 5, 6 and 7, while at the top of the bib there are two rings 7' and 8 into which 105 the buckle hooks 9 and 10 are connected.

The buckle hooks are adjustable to several positions along the length of the straps, which is to provide for a taller or shorter person as may be desired, but the adjustment 110

along the straps is not sufficient to bring the buckle to a part of the strap that is sufficiently widened to make the strap wrinkle up.

There are two straps 11, one at each side, 5 and each strap passes over the opposite shoulder of the person and is hooked to the top of the garment.

The manner of cutting the strap is illustrated in Figure 3 in which it will be seen 10 that the upper attaching corner of the strap at 15 is curved away from the lower attaching corner of the strap 16 in such a manner as to widen that end of the strap to approximately three times the width of the strap 15 as it passes through the buckle 9.

The relation of the warp of the material to the length of the strap is indicated by the broken lines in Figure 3. From this figure it will be seen that the strap is cut 20 with sufficient bias to cause all parts of the strap to lie flat on the wearer when in use. It will also be seen that in furtherance of the idea of producing a strap which will be capable of passing over the curves of the 25 body and still lie flat, that the bib of the garment is cut on the curve 17 indicated in Figure 4, which is a developed view of the bib portion of the garment shown in Fig. 2, in which figure the same edges of the bib 30 appear straight.

Having thus described my invention, what I desire to secure by Letters Patent of the United States is as follows, but modifications may be made in carrying out the invention

as shown in the drawings and in the above 35 particularly described form thereof, within the purview of the annexed claims:

1. A garment of the class described comprising an over-garment adapted to fit the lower body of the wearer, and having a 40 front bib, a pair of supporting straps each being curved throughout its length and adapted to cross each other at the back of the wearer, the lower ends of said straps being more than twice as wide as the upper 45 ends of said straps and attached to the garment at opposite sides of the wearer whereby by both the garment and the straps will be held flat on the wearer, each strap having its fastenings extending substantially vertically at its lower connection with the garment lengthwise of the sides of the wearer.

2. A garment of the class described comprising a garment to fit the lower portion of the body of the wearer, with a front bib and a pair of straps more than twice as wide at one end as at the other end, and cut on a continuous curve on the bias of the goods to lie flat upon the body of the wearer, means carried by the widest end of the 55 straps to detachably connect them to the garment along a substantially vertical line at the sides of the wearer, and means to detachably connect the garment and straps 60 together at their other ends.

In testimony whereof I have hereunto set my hand this 7th day of Jan., A. D. 1926.

GERTRUDE G. CHICK.
